[57] CLAIM

The ornamental design for a three-way T-shaped respiratory valve with dual balloon, as shown and described.

DESCRIPTION

FIG. 1 is a perspective view of a three way T-shaped respiratory valve with dual balloon showing our new design;

FIG. 2 is a left side elevational view thereof;

FIG. 3 is a front elevational view thereof;

FIG. 4 is a top plan view thereof;

FIG. 5 is a right side elevational view thereof;

FIG. 6 is a rear elevational view thereof;

FIG. 7 is a bottom plan view thereof;

FIG. 8 is a right side elevational view of a second embodiment of the three way T-shaped respiratory valve with dual balloon, wherein the body of the valve is clear thereby showing the interior thereof, the outside of the valve being otherwise the same as the valve of FIGS. 1 through 7; and,

FIG. 9 is a front elevational view of FIG. 8.
